DUMPING APPARATUS FOR OIL WELLS

Filed June 13, 1934

UNITED STATES PATENT OFFICE

2,002,112

DUMPING APPARATUS FOR OIL WELLS

Leonard E. Harrington, Long Beach, Calif., assignor to Perkins Cementing, Inc., Los Angeles, Calif., a corporation of California

Application June 13, 1934, Serial No. 730,400

10 Claims. (Cl. 166—19)

This invention relates to dumping apparatus for use in deep wells, and while the apparatus may be employed for dumping any kind of material, it is intended particularly for use in dumping acid or gelatin. Apparatus of this kind includes a holder for the material to be dumped, and below the holder a friction device is carried for engaging the wall of the casing. When the apparatus has descended in the well to a point where the material is to be released, an upward movement is given to the apparatus. In doing this, the friction device is prevented from moving upwardly by the friction on the casing, and this relative movement effects the release of the material.

One of the objects of this invention is to provide a construction for the apparatus, which will enable a valve to be employed at the bottom of the holder that comes upon its seat in a downward direction; also to provide simple means for opening a valve of this type to effect the release of the material.

In some cases it is necessary to dump the material within a liner of smaller diameter than the upper part of the casing, in the well, and one of the objects of the invention is to provide a construction for maintaining the apparatus intact and ready for operation within the liner while the dumping apparatus is descending in the well.

One of the difficulties encountered in operating this apparatus, is that if a premature opening of the valve occurs while the apparatus is descending in the well, the material or some of it will be released above the point at which the dumping operation should take place. One of the objects of this invention is to provide the apparatus with means for preventing such premature release of the material.

Further objects of the invention will appear hereinafter.

The invention consists in the novel parts and combination of parts to be described hereinafter, all of which contribute to produce an efficient dumping apparatus for oil wells.

A preferred embodiment of the invention is described in the following specification, while the broad scope of the invention is pointed out in the appended claims.

In the drawing:

Fig. 1 is a vertical section through a portion of a well casing at the location of a liner, and illustrating my apparatus in the casing just above the liner.

Fig. 2 is a vertical section through my apparatus, and illustrating the same with the parts

in normal position that is to say, the position which they have when the load of material is being retained, and the apparatus is descending in the well.

Fig. 3 is a view similar to Fig. 2, but representing the parts in the relation which they have when the apparatus is dumping its load.

Fig. 4 is a side elevation of the apparatus just below the body of the holder that carries the material, certain parts being broken away and shown partially in section.

Fig. 5 is a vertical section on the line 5—5 of Fig. 1, particularly illustrating latching means for holding the parts in their set position for descent in the well.

Before proceeding to a detailed description of the invention, it should be stated that in practicing the invention, I provide a holder for the material to be dumped, and this holder has a bottom opening. I provide a valve seating on this bottom opening from above, and I also provide a friction device located below the holder, with a lost motion connection between the same and the holder. In the operation of the dumping apparatus, by an upward movement of the holder, movable means carried on the holder, effects the opening of the valve. The apparatus is also preferably provided with an auxiliary valve above the main valve, which is so constructed that it will support the weight of the load while the dumping apparatus is descending in the well, but which will automatically open by sudden upward pull of the holder to release the load. This auxiliary valve prevents premature release of the load of material in the holder.

Referring more particularly to the parts, I indicate the upper part of a casing, the lower end of which carries a liner 2, and the connection between the casing 1 and the liner 2, usually includes a sleeve or thimble 3, having an upwardly flared mouth 4 to act as a guide for the friction device when it passes into the liner. The dumping apparatus includes a holder 5, the lower portion of which is formed with a bottom opening 6, through a valve seat 7 on which a valve, preferably of ball type such as the valve 8, seats. The material to be dumped, is held in the holder 5 above this valve 8, and if desired, this valve 8 may be employed as the sole means for retaining the load of material. Below the holder, I provide a friction device 9, which may be of any common form. This device is preferably of cage-type, comprising a plurality of bowed springs 10, which are attached at their lower ends to a collar 11 carried on a tube or long sleeve 12. Between the sleeve 12

12 and the holder 5, I provide a lost motion device, and in the operation of the dumper, when the dumper is pulled upwardly, the friction device engaging with the wall of the casing or liner 2, will be held relatively fixed. As the holder moves upwardly, this relative upward movement of the holder operates means for opening the valve 8. For this purpose I form the lower portion of the holder 5 into a guide 13, in which a movable head 14 is guided to move up and down, and this head is capable when moved upwardly, of raising the valve 8 off its seat. For this reason, I prefer to provide the head 14 with an upwardly extending stem 15, which is normally in engagement with, or just below, the under face of the valve 8. The lower portion of the guide 13 is provided with longitudinal transverse slots, to receive movable means preferably in the form of two rockers 16 mounted to rock on a transverse pin 17. Each of these rockers has an upwardly projecting toe 18, which engages the under side of the head 14, and which may raise the head 14 as indicated in Fig. 3. In order to limit the upward movement of the toes 18, I prefer to provide a stop in the form of a transverse pin 19. In order to facilitate mounting these rockers in position, they are supported on the upper side of the pin 17 by forming a notch 20 in the lower edge of the rocker, and the upper middle portion of each rocker is struck on an arc 21 having this pin 17 as its center. With this construction, the stop pin 19, being located just above this arc-shaped edge 21, retains the rockers.

Associated with the rockers, I provide actuating means for rocking them into the position indicated in Fig. 3, and this means is brought into action by upward movement of the holder 5 relative to the sleeve, or friction device 9. For this purpose, the ends of the rockers are attached to pull rods, or stems 22, which extend downwardly from the rockers and the holder. The upper ends of these pull rods are attached by pin-and-slot connections 23 to the rockers. These stems, or pull rods, are guided through guide openings 24 in the lower portion of the guide 13, and their lower ends are attached to a collar 25, which is loose on the tube, or sleeve 12. From the lower end of the guide 13, a long mandrel 26 extends downwardly, fitting into the bore of the tube, or long sleeve 12. The tube, or sleeve 12, tends by gravity to fall to the lower end of this mandrel 26, but is normally supported in an elevated position by a latch to be described hereinafter, and by frangible means preferably consisting of a cord, or light wire 27, the upper end of which is attached to the lower end of the guide 13, and the lower end of which is attached to the upper end of the friction device. The mandrel 26 has an outwardly projecting pin 28, which runs in a slot 29 in the tube, or sleeve 12, and limits the downward movement of the sleeve 12 relative to the mandrel and the holder. The frangible means such as the cord 27, is preferably maintained in taut condition by yieldingly pressing the sleeve 12 downwardly on the mandrel. For this purpose I prefer to provide a coil spring 30, which is attached to a tubular extension 13a extending down from the lower end of the guide 13. When the parts are in the relation shown in Figs. 1 and 2, the lower end of this spring thrusts against a collar 31 carried by the upper end of the tube 12. This collar 31 also has guide openings or notches 33 through which the actuating rods, or pull rods 22 pass freely. Referring

again to the friction device 9, the upper ends of the bowed springs 10 are attached to a collar 34, which is loose on the tube, or sleeve 12. Latching means is provided for holding the parts in their set position as illustrated in Fig. 1. For this purpose I prefer to provide a leaf spring 32 secured above to the side of sleeve 13a, extending down at one side, and formed with an inclined hook 32a at its lower end, that is received in an inclined slot in the under face of the collar 31 (see Fig. 5). This spring latch tends by its own resiliency to swing away from the collar, but the inclined slot prevents this while the dumper is descending the well. This latch holds the spring 30 in compression.

In the operation of the dumping apparatus constructed as described above, when the friction device 9 engages the mouth 4 of the liner 2, the bows 10 will be compressed sufficiently to permit the friction device to pass down into the liner. After the dumping apparatus has been moved down to the dumping point, then by exerting upward pull on the tool string, the friction device 9, which will be friction-tight in the liner, will release the latch and break the cord 27, whereupon the continued upward movement of the material holder 5 will eventually engage the collar 25 with the collar 31. This will exert a pull in the actuating rods 22, and that will rock the rockers so that the toes 18 of the rockers will push up the head 14 and open the valve 8. From inspection of Fig. 4, it will be noted that the guide 13 is cut away on its sides to form large openings 34a through which the dumped material can pass outwardly. The frangible cord 27 is a safety device to prevent premature release of the collar 31 while the dumper is descending in the well.

In order to prevent any premature dumping of the material, I prefer to provide the holder 5 with an auxiliary valve 36, which is preferably in the form of a check valve that opens in a downward direction from its seat 37. This valve has a stem 38, and extends upwardly from the valve, and carries a collar 39 that receives the thrust of a helical coil spring 40. This spring has sufficient force to hold the valve 36 closed against the weight of the material above this valve, but a sudden upward pull exerted on the tool string, will enable the inertia of the load 50 of material to open this valve. In other words, the same upward pull that opens the valve 8, will also open the valve 36.

The spring 30 also functions to cushion the blow if the cage 9 strikes the upper end of the liner a violent blow in its descent.

It is understood that the embodiment of the invention described herein, is only one of the many embodiments this invention may take, and I do not wish to be limited in the practice of the invention, nor in the claims, to the particular embodiment set forth.

What I claim is:—

1. In a dumping apparatus for use in deep wells, the combination of a holder for the material to be dumped having a bottom opening, a valve seating on said bottom opening from above, a friction device located below the holder, with a lost-motion connection between the same and the holder, movable means carried on the holder for effecting the opening of the valve, and means for operating said last-named movable means by an upward movement of the holder relative to the friction device.
2. In a dumping apparatus for use in deep wells,

5 wells, the combination of a holder for the material to be dumped and having a bottom opening, a valve for closing said bottom opening, a friction device located below the holder for engaging the well casing, with a lost-motion connection between the same and the holder, means brought into operation by an upward movement of the holder relative to the friction device for opening the valve, and an auxiliary valve in the holder above the first-named valve, opening in a downward direction, said auxiliary valve operating to prevent release of the material in case the first-named valve opens prematurely, while the dumping apparatus is descending in the well.

10 15 3. In a dumping apparatus for use in deep wells, the combination of a holder for the material to be dumped and having a bottom opening, a valve for closing said bottom opening, a friction device located below the holder for engaging the well casing, with a lost-motion connection between the same and the holder, means brought into operation by an upward movement of the holder relative to the friction device for opening the valve, and an auxiliary valve in the holder above the first-named valve, opening in a downward direction, and means for resisting the downward movement of the auxiliary valve, said auxiliary valve operating to prevent release of the material in case the first-named valve opens prematurely, while the dumping apparatus is descending in the well.

20 25 4. In a dumping apparatus for use in deep wells, the combination of a holder for the material to be dumped having a bottom opening, a valve seating on said bottom opening from above, a stem located below said valve, means for guiding the lower end of said stem on said holder, movable means supported on the holder operating when actuated, to raise the stem, and thereby move the valve off its seat, a friction device located below the holder for engaging the casing, with a lost-motion connection between the same and the holder, and means brought into action by upward movement of the holder relative to the friction device for actuating said movable means to open the valve.

30 35 5. In a dumping apparatus for use in deep wells, the combination of a holder for the material to be dumped having a bottom opening, a valve seating on said bottom opening from above, a friction device located below the holder, with a lost-motion connection between the same and the holder, movable means carried on the holder for effecting the opening of the valve, means for operating said last named movable means by an upward movement of the holder relative to the friction device, and a spring mounted between the holder and the friction device exerting its force to resist upward movement of the friction device relative to the holder.

40 45 6. In a dumping apparatus for use in deep wells, the combination of a holder for the material to be dumped having a bottom opening, a valve seating on said bottom opening from above, a friction device located below the holder, with a lost-motion connection between the same and the holder, movable means carried on the holder for effecting the opening of the valve, means for operating said last named movable means by an upward movement of the holder relative to the friction device, a spring mounted between the holder and the friction device exerting its force to resist upward movement of the friction device relative to the holder, and means for holding the friction sleeve in a relatively raised position

5 against the force of said spring while the dumping apparatus is descending in the well.

7. In a dumping apparatus for use in deep wells, the combination of a holder for the material to be dumped having a bottom opening, a valve seating on said bottom opening from above, a stem located below said valve, means for guiding the lower end of said stem on said holder, a rocker mounted on the holder for actuating the stem to raise the valve off its seat, a friction device located below the holder for engaging the casing, with a lost-motion connection between the same and the holder, and means brought into action by upward movement of the holder relative to the friction sleeve for actuating said rocker to open the valve.

10 15 8. In a dumping apparatus for use in deep wells, the combination of a holder for the material to be dumped having a bottom opening, a valve seating on said bottom opening from above, a stem located below said valve, means for guiding the lower end of said stem on said holder, a head carried on said stem, a pair of rockers mounted on the holder below the head for lifting the head to open the valve, actuating rods connected with said rockers and extending downwardly, a friction device located below the holder for engaging the casing, with a lost-motion connection between the same and the holder, and means connected with the sleeve for effecting a relative movement of said actuating rods brought into action by upward movement of the holder relative to the friction sleeve, for actuating said rockers to open the valve.

20 25 9. In a dumping apparatus for use in deep wells, the combination of a holder for the material to be dumped having a bottom opening, a valve in the form of a ball seating on said bottom opening from above, a stem guided to move substantially vertically in the holder below the valve for raising the same off its seat, a head carrying said valve stem and guided in the holder below the valve, a pair of rockers carried by the holder and having means for raising the head to open the valve, actuating rods for the rockers extending downwardly from the rockers, a friction device located below the holder, having a sleeve extending upwardly therefrom, said sleeve having means for imparting a relative downward movement to said actuating rods brought into action by an upward movement of the holder relative to the friction device, and a lost-motion connection between the friction device and the holder.

30 35 10. In a dumping apparatus for use in deep wells, the combination of a holder for the material to be dumped having a bottom opening, a valve seating on said bottom opening from above, a stem located below said valve and capable of upward movement to open the valve, movable means supported on the holder for raising the stem to open the valve, a friction device located below the holder for engaging the well casing, with a lost-motion connection between the same and the holder, a spring in the space between the holder and the friction device resisting upward movement of the friction device relative to the holder, and releasable means connecting the holder and the friction device operating to be released by the frictional force exerted by the well casing on the friction device when upward movement of the holder occurs relative to the friction device.

LEONARD E. HARRINGTON.
